US0D1040294S

(12) **United States Design Patent** (10) **Patent No.:** **US D1,040,294 S**
(45) **Date of Patent:** **** Aug. 27, 2024**

(54) **AIR CONDITIONER**

(71) Applicants: **GD MIDEA AIR-CONDITIONING EQUIPMENT CO., LTD.**, Guangdong (CN); **MIDEA GROUP CO., LTD.**, Guangdong (CN)

(72) Inventors: **Zizheng Zhang**, Guangdong (CN); **Hiho Jung**, Guangdong (CN); **Yan Zhang**, Guangdong (CN)

(73) Assignees: **GD MIDEA AIR-CONDITIONING EQUIPMENT CO., LTD.**, Guangdong (CN); **MIDEA GROUP CO., LTD.**, Guangdong (CN)

(**) Term: **15 Years**

(21) Appl. No.: **29/837,115**

(22) Filed: **May 2, 2022**

(30) **Foreign Application Priority Data**

Jan. 24, 2022 (CN) 202230047411.1

(57) **CLAIM**

The ornamental design for an air conditioner, as shown and described.

DESCRIPTION

FIG. 1 is a left, front, bottom perspective view of an air conditioner of the present disclosure;

FIG. 2 is a right, front, top perspective view thereof;

FIG. 3 is a front elevational view thereof;

FIG. 4 is a rear elevational view thereof;

FIG. 5 is a left-side elevational view thereof;

FIG. 6 is a right-side elevational view thereof;

FIG. 7 is a top plan view thereof; and,

FIG. 8 is a bottom plan view thereof.

The broken lines shown in the drawings illustrate portions of the air conditioner that form no part of the claimed design.

1 Claim, 8 Drawing Sheets
